CENTRIFUGAL BLOWER WHEEL

Einar Lunde and William T. Nichols, La Crosse, Wis., assignors to The Trane Company, La Crosse, Wis., a corporation of Wisconsin

Application March 1, 1956, Serial No. 568,793

5 Claims. (Cl. 230—134)

This invention relates to improvements in centrifugal blower wheels and more particularly to an improved arrangement for assembling the cylindrical body structure of a blower wheel to an associated hub plate.

Heretofore in the manufacture of centrifugal blower wheels, the process of assembling the large number of parts required for the complete wheel has been a time consuming and expensive operation. The blade structure of this invention is such that the fan blades are assembled into a unitary flexible strip by the machine which forms the blades. By reason of this construction, the number of parts required for a complete wheel is reduced and the assembly of the wheel is simplified.

It is an object of this invention to provide a blade structure by which the blades are interlocked into a unitary flexible strip.

It is another object of the invention to provide a blade structure by which flanges on the blades form rim portions of the wheel.

It is another object to provide a blower wheel which has a maximum effective blade length with only a relatively small space at the ends for blade retention.

It is still another object of the invention to provide a centrifugal blower wheel in which the parts thereof can be assembled very rapidly so that the wheels can be manufactured in quantities with low cost for labor and material.

Other objects and advantages of the invention will become apparent as the specification proceeds to describe the invention with reference to the accompanying drawings in which:

Figure 1 is a sectional view of the blower wheel taken on line 1—1 of Figure 5;

Figure 2 is an exploded perspective view of a portion of the blower wheel showing the blade structure;

Figure 3 is an elevational end view of a blade before the interlocking tabs have been formed over;

Figure 4 is a partial side view of a blade with the interlocking tabs completely formed;

Figure 5 is a sectional view of a single width wheel taken on line 5—5 of Figure 1;

Figure 6 is a sectional view of a double width wheel taken on an axial plane;

Figure 7 is an elevational view of part of a wheel showing the weld securing the blades together at the end remote from the hub plate.

Referring now to the drawings and particularly Figures 1 and 2, numeral 10 designates a hub plate to which is secured a hub 12 and blades 14. The blade 14 has a vane portion 16 which is arcuate or substantially arcuate in cross-section and a flange base portion 18 at each end extending at right angles to the vane portion 16. Extending from the flange base portions 18 are flange end portions 20 offset outwardly from the flange base portions 18 so that the flange end portions 20 will receive therebetween the flange base portions 18 of the next adjacent blade. The shoulder 19 between the flange base portion and the flange end portion has a radius of curva-

ture substantially the same as the convex surface of the vane portion 16 of the blade.

The flange base portion 18 of each blade has a recessed outer edge 21 and a recessed inner edge 22 both of circular form and having their axes of curvature substantially at the axis of curvature of the convex surface of the vane portion 16 of the blade. The flange end portion 20 of each blade has inwardly extending interlocking tabs 24 and 26 which engage in the recessed outer edge 21 and the recessed inner edge 22 respectively of the flange base portion of the next adjacent blade to hold the blades in the form of a flexible strip leaving the blade forming press. The interlocking tabs 24 of the first blade of a blade assembly are not formed over but lie in the plane of the flange end portion 20 as shown in Figures 2 and 3. The interlocking tabs 24 and 26 of succeeding blades are formed over to lock the blade to the next preceding blade. In this manner the blade forming press interlocks the required number of blades for the wheel.

20 A strip having the required number of blades 14 for a given wheel is then placed on a fixture having a cylindrical outer surface strip and the tabs 24 of the first blade are formed over against the recessed outer edges 21 of the last blade using a hand tool.

25 A hub 12 is secured to the hub plate 10 in any suitable manner as by swaging the flange 30 against the hub plate. A hub plate 10 having the hub thereon is placed on the fixture with the inwardly extending bead 32 of the hub plate engaging the inner edge of one end of the blade assembly as shown in Figure 5. The blade assembly and the hub plate are then welded together by arc welding a bead 34 to join the end flanges of the blades 14 at one end of the wheel while simultaneously welding a bead 36 to join the end flanges of the blades 14 at the other end to each other and to the hub plate 10.

30 Figure 6 shows a double width wheel. In making this wheel a hub plate 10 is placed in the fixture and a blade assembly is placed in the fixture on each side of the hub plate 10. A welding bead 38 is then produced at the outer ends of the blade assembly to join the end flanges of the blades 14, and simultaneously therewith a welding bead 40 is produced to join the inner end flanges of the blades to each other and to the hub plate 10.

35 It should be understood that although we prefer to use arc welding, other forms of welding may be used. For instance the end flanges of the blades may be secured to each other and to the hub plate by gas welding or electric resistance welding or by solder dipping. It is also contemplated that the wheel assembly can be made by 40 brazing the end flanges of the blades and the hub plate 10 to each other at their areas of contact. When the wheel is made of aluminum, the welds may be made by the salt bath brazing process, and surfaces to be welded have a thin coating of an alloy having a lower melting 45 temperature than the base metal.

50 While we have described the foregoing preferred embodiments of our invention, we contemplate that many changes may be made without departing from the scope or spirit of our invention, and we desire to be limited 55 only by the claims.

We claim:

56 1. A centrifugal blower wheel comprising a plurality of blades, each of said blades having flanges thereon lying in planes which are substantially radial of said 60 wheel, the flanges of the blades overlapping the flanges of the next adjacent blades, interlocking means on the side edges of said flanges to hold the blades together, said flanges being merged together in a weld to form 65 wheel rims, and a hub plate welded to one of said wheel 70 rims.

66 2. In a centrifugal blower wheel the combination of 75 a plurality of blades, each of said blades having a vane

portion and flanges extending from each end of the vane portion with said flanges lying in planes which are substantially normal to said vane portion, each of said flanges having a base portion and an outwardly offset end portion, the outwardly offset end portions of the flanges of each blade receiving therebetween the base portions of the flanges of the next adjacent blade, said flanges having recesses in their side edges and tabs extending from their side edges and extending into the recesses of the flanges of the next adjacent blade, means welding said offset end portions of the flanges to said base portions of the flanges received therebetween to form continuous wheel rims.

3. In a centrifugal blower wheel the combination of a plurality of blades, each of said blades having a vane portion and flanges extending from each end of the vane portion with said flanges lying in planes which are substantially normal to said vane portion, each of said flanges having a base portion and an outwardly offset end portion, the outwardly offset end portions of the flanges of each blade receiving therebetween the base portions of the flanges of the next adjacent blade, recesses in the edges of said flanges and tabs on the edges of said flanges, said tabs extending into the recesses of the flanges of the next adjacent blade.

4. In a centrifugal blower wheel the combination of a plurality of blades, each of said blades having a vane portion and flanges extending from each end of the vane portion with said flanges lying in planes which are substantially normal to said vane portion, each of said flanges having a base portion and an outwardly offset end portion, the outwardly offset end portions of the flanges of each blade receiving therebetween the base portions of the flanges of the next adjacent blade, recesses in the edges of said flanges and tabs on the edges of said flanges, said tabs extending into the recesses of the flanges of the next adjacent blade.

the flanges of the next adjacent blade, recesses in the edges of said flanges and tabs on the edges of said flanges, said tabs extending into the recesses of the flanges of the next adjacent blade, means welding together the flanges at one end of the wheel, a hub plate abutting the other flanges of the blades and means welding together the hub plate and said other flanges of the blades.

5. In a centrifugal blower wheel the combination of an annular row of blades, each of said blades having a vane portion and flanges extending from each end of the vane portion with the flanges lying in planes substantially normal to said vane portion, each of said flanges having a base portion and an outwardly offset end portion, the outwardly offset end portions of the flanges of each blade receiving therebetween the base portions of the flanges of the next adjacent blade, a continuous annular bead welded to the base portions and end portions of the flanges of the blades at one end of the wheel, a hub plate abutting the other flanges of the blades, and means at the periphery of said hub plate welding together the hub plate and said other flanges of the blades.
